PROCESS OF PRODUCING AN ANTIOXIDANT CONCENTRATE

Loran Old Buxton, Maplewood, N. J., assignor to Nepeco Chemical Company, Harrison, N. J., a corporation of New Jersey

No Drawing. Application January 22, 1947,
Serial No. 723,651

17 Claims. (Cl. 252—398)

1

This invention relates to the production of antioxidants and to the stabilization of oxidizable organic substances, primarily those of an oily or fatty nature.

It is well known in the art that many oxidizable organic substances, e. g. oils, fats and waxes containing fatty acid radicals, as well as soaps thereof, tend to be detrimentally affected by exposure to atmospheric conditions for prolonged periods of time. For example, many oils and fats tend to develop considerable rancidity and undesirable tastes and odors upon prolonged exposure to air. This instability of oils and fats tends to be accentuated by conventional refining processes since in many cases the refining destroys or removes the natural antioxidants contained in such substances. This characteristic instability is particularly undesirable in connection with fat-soluble vitamin-containing oils, since these oils not only show the typical tendency to become rancid upon exposure to air, but also tend to lose a considerable portion of their valuable activity. Other oxidizable organic substances manifest their characteristic instabilities in different fashions, but in practically every case their instability is highly undesirable.

As a result of the instability shown by many oxidizable organic substances, many attempts have been made to increase the resistance of these substances to the action of oxidizing influences. In a few cases there has been a fair amount of success in stabilizing fatty materials against deteriorative oxidation. However, a large number of the suggested methods for producing antioxidants and stabilizing fatty materials against oxidation have not been too successful. In many cases the potency of the antioxidants obtained has been low, and as a result the stability of the fatty materials to which they were added has not been satisfactory. In some instances the antioxidants obtained have not been sufficiently miscible with the fatty materials to give a stable, desirable product. In other cases the antioxidants have had rather undesirable tastes and odors which they in turn imparted to any material to which they were added to inhibit oxidation. In view of these and other disadvantages in prior processes for producing antioxidants and stabilizing fatty materials, there is still a considerable demand for improved, potent antioxidants which will effectively stabilize fatty materials against deteriorative oxidation.

It is the object of this invention to provide an improved process for obtaining highly potent antioxidants.

A further object of this invention is to provide improved, highly potent antioxidants which will effectively stabilize fatty materials against oxidative changes.

2

Another object of this invention is to provide improved, highly potent antioxidants which will effectively prevent loss of potency in vitamin A or D containing fatty materials.

Other objects of the invention will in part be obvious and will in part appear hereinafter.

I have discovered that the above and other objects of the invention may be achieved by contacting a crude vegetable oil with concentrated ammonia and subsequently fractionating the fatty material with a solvent substantially miscible with fatty materials at room temperature but only partially miscible therewith at temperatures somewhat below room temperature, and recovering a highly potent antioxidant concentrate in that portion of the solvent which is relatively immiscible with the fatty material at temperatures somewhat below room temperature. This antioxidant is very effective in stabilizing fatty materials, and particularly fatty materials containing vitamins A or D, against oxidation.

In carrying out the process of my invention, a crude vegetable oil is first treated with concentrated ammonia. Crude vegetable oils suitable for use in the process of my invention include, among others, the crude vegetable oils contained in oil-bearing seeds and nuts such as soybeans, peanuts, corn, wheat, cottonseed, sesame seed, rice, rye, barley, oats, coconuts, etc.

In carrying out the ammonia treatment step of the process of my invention, the crude oil may be contacted with ammonia under varying circumstances. For example, the crude vegetable oil may be removed from its source material and then contacted with the ammonia; the crude vegetable oil may be contacted with ammonia prior to removal from the source material, i. e. by contacting an oil-bearing vegetable meal or other vegetable material containing the desired oil with the ammonia; or a crude vegetable oil may be added to a quantity of the same or a different type of vegetable material from which the oil was derived which vegetable material may have had none or any varying amount up to all of its original oil content previously removed therefrom, and then contacting the crude vegetable oil in such admixture with the ammonia. Naturally, of course, in the above procedures, instead of treating just one individual crude vegetable oil or a crude oil in conjunction with just one individual vegetable material, any suitable mixtures of such oils either alone, in the first case, or associated with a vegetable material or suitable mixture of such materials, in the latter two cases, may be treated. Furthermore, if desired, a vitamin-containing oil or concentrate may be admixed with the crude vegetable oil or oil-bearing vegetable material and such mixture treated in accordance with the process of the invention. By operating in such a manner, a very

stable and highly potent vitamin concentrate may be produced.

When the ammonia treatment is carried out on a crude vegetable oil associated with vegetable materials, the vegetable materials are preferably ground, chopped, flaked, comminuted or otherwise finely divided prior to the ammonia treatment. Many oil-bearing vegetable materials are commercially available in the meal form such as, for example, cottonseed meal, soybean meal, sesame meal, corn meal, corn germ meal, wheat germ meal, alfalfa leaf meal, peanut meal, rice bran, and rye, barley and other similar vegetable meals. The oil content of these vegetable materials varies considerably, of course. When treating a crude vegetable oil without removing it from the original source material, it is usually preferred to employ a vegetable material which has a relatively high oil content; however, quite excellent results may be obtained by carrying out the process upon vegetable materials having a rather low oil content. In most cases, however, it is preferred to employ oil-bearing vegetable materials containing at least 5% of oil. Whenever the term "oil-bearing vegetable meal" is used in the specification and claims it is to be understood that the term connotes any of the oil-bearing vegetable materials as set forth in the specification.

When the ammonia treatment is carried out upon a crude vegetable oil which has been admixed with the same or a different type of vegetable material from which the crude oil was derived, the vegetable material may still contain its original oil content, or it may have had any varying amount up to and including all of its original oil content removed. The crude vegetable oils may be obtained from any of the various oil-bearing vegetable materials listed above or from other sources. Likewise the vegetable materials employed may be any of those listed above or any other suitable vegetable material. The vegetable oil added to the vegetable material may be the same oil as is obtainable from the vegetable material or it may be an entirely different vegetable oil. Since it is preferred in some cases when treating a crude vegetable oil associated with a vegetable material to treat such a vegetable material containing a fairly high percentage of oil, e. g. 40% to 50% of oil, it is desirable in some instances to increase the oil content of a vegetable material which already contains in its natural state a considerable amount of oil. Thus in some cases it may be preferred to add a sufficient amount of a vegetable oil to an oil-bearing vegetable material containing, for example, 20% of oil to bring its oil content up to as high as 40% or 50% or more. The vegetable oil which is added to a vegetable material already containing a considerable amount of oil may be the same oil as is obtainable from the vegetable material, or it may be an entirely different vegetable oil.

The concentrated ammonia which is employed in the process of my invention is preferably 28% aqueous ammonia. However, other concentrated aqueous solutions of ammonia as well as gaseous ammonia or liquid ammonia may be utilized. The amount of ammonia used is relatively small as compared to the amount of vegetable oil. At least about 1% by weight of 28% aqueous ammonia as compared to the weight of the material being treated should be employed. Ordinarily I prefer to employ from about 20% to about 60% of 28% aqueous ammonia based upon the weight of the material being treated. If desired, even

4
much larger amounts of ammonia may be used, e. g. 100% or more; however, the use of such large amounts of ammonia while not being detrimental is not particularly advantageous. When other forms of ammonia are being employed, the amounts used are equivalent to that just set forth.

Preferably the crude vegetable oil is treated with the ammonia in the presence of a solvent for the oil. However, it is not necessary to carry out the treatment in the presence of a solvent, and in some cases it may be preferred not to do so. For example, in the event that ammonia gas is used, the process may be carried out in a closed vessel under pressure of the ammonia gas. The length of time of contact of the crude vegetable oil with the ammonia will vary depending upon whether or not the treatment is carried out in the presence of a solvent for the oil and whether the treatment is carried out at room temperature or at elevated temperatures. Both the presence of the solvent and increased temperatures will accentuate the action of the ammonia and thus reduce the amount of time necessary for the treatment step. When treating the crude oil in the presence of a solvent, it is preferred to heat the mixture at the reflux temperature of the solvent for a short time, e. g. half an hour to an hour although it may be heated longer, if desired. The heating may be carried out in an inert atmosphere, e. g. in the presence of nitrogen gas, if desired.

Oil solvents which may be used in the ammonia treatment step of my process include hydrocarbon and halogenated hydrocarbon solvents such as hexane, heptane, octane, ethylene dichloride, trichloroethylene, carbon tetrachloride, cyclohexane, methyl cyclohexane, benzene, etc., as well as solvents such as acetone, isopropanol, diacetone alcohol and the like. Of these many solvents I prefer to employ acetone as it appears to give the most favorable results in the process. However, any of the other solvents will give excellent results, and they, or any desired mixtures thereof, may be used if desired.

If the process of the invention has been carried out upon a crude vegetable oil associated with a vegetable meal, or other similar vegetable material, the solvent with the crude oil dissolved therein, is separated from the vegetable meal after the ammonia treatment has been completed, and the meal is then washed with additional portions of the same oil solvent, or a different oil solvent, if desired, to completely remove the oil therefrom. If no oil solvent has been employed in the ammonia treatment step of the process, the oil containing the highly potent anti-oxidants may be removed from such vegetable material by washing the same with one of the oil solvents listed above. However, if desired, the treated oil-bearing vegetable material may be dried by exposure to the atmosphere, or by any other suitable means, thus removing the ammonia and the greater part of any oil solvent employed in the ammonia treatment step. The fatty material may then be removed from the treated oil-bearing vegetable material by extraction with any suitable oil solvent. Instead of removing the oil from the oil-bearing vegetable material by means of solvent extraction, other conventional means of removing the oil from the oil-bearing vegetable material, e. g. the expeller process or the hydraulic process, may be employed to remove the oil in all the above cases from the oil-bearing vegetable material.

The ammonia treated oil will have dissolved therein a large amount of highly potent antioxidants. The exact nature of these antioxidants has not yet been determined. No doubt a large percentage of these antioxidants were originally present in the crude vegetable oil, and in the vegetable meal or similar vegetable material if such were employed in the process of the invention, and the effect of the ammonia treatment was to release these antioxidants with much greater efficiency than has ever been done heretofore. However, it is very probable that the ammonia also reacted with certain of the original antioxidants in such a manner as to greatly increase their potency or to produce therefrom new antioxidants of greater potency than the original antioxidants. Furthermore, it may be that the ammonia treatment converts certain compounds in the vegetable oil and vegetable meal which themselves have no antioxidant activity into materials which are excellent antioxidants. The most probable explanation is that a combination of all of the above occurs. Whatever may be the true explanation, I have discovered that the treatment as outlined hereinabove produces very highly potent antioxidants. However, since they are dissolved in a relatively large amount of oil, it is desirable that they be concentrated by separating them from the bulk of the oil.

If a crude vegetable oil has been treated in association with a vegetable meal or similar material, the treated oil may be separated from the solvent used to remove the oil from the treated oil-bearing vegetable material following the ammonia treatment step by simply distilling off the solvent; however, if such oil solvent is one which is suitable for use in the solvent extraction step of the process, no such separation need be made. Instead a sufficient amount of solvent to obtain the desired ratio of solvent to oil is either added to or removed from the solution whichever may be necessary, if either.

In carrying out the separation of the antioxidants from the highly potent oil solution thereof, the oil is mixed with a solvent which is substantially miscible with fatty materials at room temperature, i. e. 20°-25° C. and partially immiscible therewith at temperatures somewhat below room temperature, e. g. 0° C. or below. Such solvents which I have found to be suitable for use in the process of my invention fall into several well-defined classes. The following table sets forth the classes of solvents which I have found to be particularly useful in the solvent extraction step of my invention.

Table I

1. Aliphatic and alicyclic monohydroxy alcohols containing from 3 to 6 carbon atoms.

2. Esters formed by the reaction of aliphatic and alicyclic alcohols with aliphatic monocarboxylic acids, said esters containing not more than 8 carbon atoms.

3. Aliphatic and alicyclic aldehydes containing not more than 6 carbon atoms.

4. Aliphatic ketones containing not more than 6 carbon atoms.

Solvents falling in the classes above listed are all liquid aliphatic organic compounds having the properties of being substantially miscible with fatty materials at temperatures above room temperature, i. e. 20° to 25° C., and partially immiscible therewith at temperatures somewhat below room temperature. The temperature at which

these various solvents become partially immiscible with fatty materials will vary. In practically all cases these solvents are partially immiscible with fatty materials at temperatures of 0° C. or below. However, a few of these solvents, e. g. isopropanol, are partially immiscible with fatty materials at temperatures only slightly below room temperature. My experiments have shown that solvents falling within the above classes of compounds may be used in the practice of my invention. In addition it will be noted that my preferred solvents possess relatively low freezing points.

In order to more fully illustrate the nature of the solvents which I may employ, a partial list thereof is herewith given; it is to be understood, however, that this list is not intended to be complete, but is merely illustrative of the solvents which may be employed. Thus I have found that the following solvents may be used: n-propyl alcohol, isopropyl alcohol, n-butyl alcohol, n-amyl alcohol, isoamyl alcohol, secondary amyl alcohol, furfuryl alcohol, allyl alcohol, diacetone alcohol, β -hydroxy ethyl acetate, methyl formate, ethyl formate, ethyl acetate, methyl acetate, isopropyl acetate, glycol formate, glycol diacetate, methyl levulinic, ethyl levulinic, methyl aceto acetate, ethyl aceto acetate, methyl furoate, vinyl acetate, furfural, propionaldehyde, crotonaldehyde, acetone, methyl ethyl ketone, acetyl acetone and propylene chlorhydrin. Mixtures of these solvents may also be used. It will be noted that all these solvents belong to that class of aliphatic organic compounds which have the properties of being miscible with fatty materials at temperatures above room temperature and partially immiscible therewith at temperatures somewhat below room temperature; furthermore, it will be noted that the majority of these solvents have relatively low freezing points.

Occasionally it may be found that certain of the solvents hereinabove mentioned may be too miscible with some of the fatty materials which may be treated by my invention to effect a separation of antioxidants therefrom; thus, for example, acetone is too miscible with many fatty materials to accomplish the purposes of my invention. However, this condition may be easily corrected by diluting the solvent either with a small amount of water or with some liquid aliphatic organic solvent relatively immiscible with fatty materials. In general it may be said that the effect of diluting any of the above solvents with water will be to render the solvent more immiscible with fatty materials, so that if difficulty is encountered in effecting proper separation of the antioxidant extracts from the fatty materials, this difficulty may generally be overcome by the addition of a small amount of water to the solvent. Furthermore the degree of cooling which will be required to bring about the partial immiscibility of the solvent with a fatty material will be less with such a diluted solvent as compared to the undiluted solvent.

The solvents I prefer to employ in the practice of my invention are acetone and the aliphatic alcohols containing from 3 to 6 carbon atoms; of the alcohols isopropanol and diacetone alcohol have proved to be the most successful. The presence of the hydroxyl group in the alcohols seems to impart to these solvents properties which make them particularly useful for my purposes; whether this factor is due to some activating influence possessed by this group is not known.

In carrying out the separation of the antioxidants from the highly potent oil solution thereof, the oil is mixed with one of the solvents which is substantially miscible with fatty materials at room temperature, but only partially miscible therewith at temperatures somewhat below room temperature. The relative proportion of oil to solvent may vary widely; preferably the ratio of solvent to oil should be greater than one, and in most cases mixtures containing between about 2% and about 25% oil are most suitable. It is preferable to cause substantially all of the oil to dissolve in the solvent; complete solution may be readily effected by heating the mixture to a temperature substantially above room temperature. However, it is not necessary to cause the oil to dissolve completely in the solvent, since the antioxidants may be very effectively extracted from the oil solution thereof by agitating the oil with the solvent at a temperature such that only partial solution is effected. In fact, the complete extraction step may be carried out at temperatures substantially below room temperature, if desired, in which case the solvent and the oil will at no time be completely miscible. The extraction may be carried out, if desired, in an inert gas atmosphere, e. g. in the presence of nitrogen gas. When the process of the invention is carried out on a crude vegetable oil associated with a vegetable meal, it is preferred to separate the oil from the vegetable meal prior to carrying out the fractionation step. However, such removal may be dispensed with, if desired, and the fractionation step may be carried out directly upon the treated oil-bearing vegetable material by contacting the fractionating solvent therewith.

The antioxidant concentrate may be recovered in any suitable manner. When operating in accordance with the preferred method of solvent extraction, i. e. when the oil is completely dissolved in the solvent at somewhat elevated temperatures, the recovery of the antioxidant concentrate is most conveniently accomplished by cooling the solution to a temperature sufficiently below room temperature so that two layers will form, a solvent layer and an oil layer. In every case the solvent layer will contain practically all of the antioxidants. In most cases such layer formation takes place on cooling the solution to approximately 0° C. However, in some instances, cooling of the solution just a few degrees below room temperature will bring about the desired layer formation. In such cases, of course, the solution need not be cooled to a temperature as low as 0° C. As long as the solution is cooled to a temperature where layer formation occurs, such cooling will be sufficient to effect the purposes of the invention. In most cases I prefer to cool the solution to at least 0° C. and even as low as -18° C., since such lower temperatures more effectively concentrate the antioxidants in the solvent layer. However, as pointed out above, as long as the cooling is sufficient to cause the solution to separate into a solvent layer and an oil layer, excellent concentration of the antioxidants will be brought about. Regardless of the method by which the separation of the antioxidants from the oil is effected, it will be found that they will be concentrated in that portion of the solvent which is substantially immiscible with the oil at temperatures somewhat below room temperature. If desired the extraction step may be repeated one or more times to ensure com-

plete recovery of the antioxidants. Also, a continuous countercurrent extraction process may be utilized, if desired, rather than using a batch process.

5 The solvent solution which is immiscible with the oil at the low temperature may be filtered, if desired, and then treated to remove the solvent therefrom, e. g. by vacuum distillation. On the removal of the solvent, an antioxidant concentrate far more potent than any previously produced will be obtained. If desired, water may be added to the concentrate to precipitate any glycerides therein or some of the sterols may be removed; however, these steps are not essential since the glycerides and sterols do not inhibit the antioxidant properties of the concentrate. If the ammonia employed in the ammonia treatment step of the process has not already been evaporated or distilled off incidental to the previous steps of the process, it will be removed in the final step of the process when the extracting solvent is removed from the antioxidant concentrate.

25 Although the exact nature of these antioxidants has not yet been determined, I have observed that the antioxidant concentrates have a lower iodine value than the vegetable oils from which they are derived.

30 My novel antioxidants may be employed for the stabilization of all types of oxidizable organic substances, particularly those of a fatty nature, i. e. fatty oils, fats, waxes, soaps, vitamin concentrates, etc. Thus oils and fats of animal, vegetable or fish origin, such as cod liver oil, tuna liver oil, shark liver oil and other fish liver oils, as well as vitamin concentrates or vitamin-containing fractions obtained from such oils; corn oil, cotton seed oil, soybean oil and other vegetable oils; fats such as butter, margarine, lard, hydrogenated shortenings, palm oil, etc.; soaps of higher fatty acids; and compositions containing such fatty materials as essential ingredients, e. g. food emulsions such as mayonnaise, may all be suitably stabilized in accordance with my invention. Furthermore, substances such as sulfonated oils and other sulfonated fatty compounds, amides, mono and diglycerides and other fatty substances which tend to become rancid upon exposure to air may be treated by my invention. The amount of the extract added to the fatty material to be stabilized may vary considerably, depending upon the activity of the extract and the degree of instability of the fatty material; I have found that oils or fats containing anywhere from about 0.1% to about 20%, preferably from about 0.5% to about 5% of my antioxidant extracts show striking improvements in their stability.

60 While my invention is primarily concerned with the stabilization of oxidizable organic substances of a fatty nature, other oxidizable organic substances, such as rubber, substances containing vitamin C, pyrethrum, essential oils and other materials known to the art may be stabilized by treatment with my novel extracts.

65 For a fuller understanding of the nature and objects of the invention reference may be had to the following examples which are given merely to further illustrate the invention and are not to be construed in a limiting sense.

Example I

Several samples of crude vegetable oils were treated with concentrated aqueous ammonia in the presence of acetone by mixing for about one

hour at a temperature of about 55° C. under reflux conditions. The acetone and ammonia were then removed from the oil by distillation under reduced pressure. Portions of the treated oils were then fractionated with 91% isopropanol, two extractions being made in each case with a ratio of four parts of solvent to one part of oil being employed. The solvent and the oil were contacted at room temperature, then cooled to a temperature of -18° C. Two layers formed in each case at slightly below room temperature; however, the mass was cooled to the lower temperature in order to obtain a more efficient concentration of the antioxidants. The solvent layer was separated from that portion of the oil immiscible therewith, and a highly potent antioxidant concentrate was recovered in each case upon removal of the solvent from the solvent layer by distillation under reduced pressure.

The relative potencies of these antioxidants were compared with the potencies of antioxidants prepared by the process of my U. S. Patent No. 2,345,576 patented April 4, 1944 by admixing with various samples of a refined shark liver oil, amounts of the various antioxidants equal to 3% of the weight of each shark liver oil sample. The stability of these samples of shark liver oil was then determined by maintaining the samples at a temperature of 34.5° C. in contact with the atmosphere, and measuring the percentage of vitamin A loss in each sample after a definite number of days had elapsed. A control experiment on an unstabilized sample of refined shark liver oil was also conducted.

Further details and the results of the above experiments are given in the following table:

masses were air dried at room temperature in open trays. The treated air-dried materials were then extracted with ethylene dichloride to remove the fatty material. These solvent extracts were filtered, and the solvent removed therefrom by distillation under reduced pressure. Portions of the fatty materials were then fractionated with various of the fractionating solvents listed hereinabove, two extractions being made in each case with a ratio of four parts of fractionating solvent to one part of fatty material being employed. The solvent and the fatty material were contacted at room temperature and then cooled to a temperature of -18° C. Two layers formed at slightly below room temperature; however, by cooling to the lower temperature a more efficient concentration of the antioxidants was obtained. The solvent layer was separated from that portion of the fatty material immiscible therewith, and a highly potent antioxidant concentrate was recovered in each case upon removal of the solvent from the solvent layer by distillation under reduced pressure.

To demonstrate the stabilizing action of these antioxidants, various samples of a refined shark liver oil were admixed with amounts of the antioxidants equal to 3% of the weight of each shark liver oil sample. The stability of these samples was then determined as in Example I. A control experiment on an unstabilized sample of shark liver oil was also conducted. To further show the potency of the antioxidant concentrates of this invention, several samples of shark liver oil were stabilized by adding thereto antioxidant concentrates prepared by the fractionation of fatty materials extracted from untreated

11
Example III

Several samples of relatively oil-free vegetable materials were admixed with various crude vegetable oils, and the resulting oil-bearing vegetable materials were processed as in Example II to produce highly potent antioxidant concentrates.

The potency of the antioxidant concentrates was determined as in Example I. For purposes of comparison control experiments on unstabilized samples of shark liver oil were also conducted. Also samples of the various crude vegetable oils employed to increase the oil content of the relatively oil-free vegetable materials were fractionated, and the potency of the resulting antioxidant concentrates compared with that of the antioxidant concentrates prepared by the process of the present invention. In each case when an antioxidant concentrate was added it was added in an amount equal to 3% of the weight of the oil being stabilized.

Details and results of the above experiments are given in the following table. In each case when the fatty material was extracted from the vegetable oil-vegetable meal mixture, three extractions with ethylene dichloride were made employing a ratio of one to one (mls./gms.) of solvent to vegetable oil-vegetable meal mixture.

¹ This example shows the use of an antioxidant concentrate prepared by the process of my U. S. Patent No. 2,345,876, patented April 4, 1944.

Having described my invention, what I claim as new and desire to secure by Letters Patent is:

1. In a process for producing an antioxidant concentrate, the steps comprising contacting a crude vegetable oil with ammonia, contacting the ammonia-treated oil with a solvent substantially miscible with fatty materials at room temperature and only partially miscible therewith at temperatures somewhat below room temperature, and separating a solvent solution containing a highly active antioxidant extract from the oil immiscible with the solvent at the temperature somewhat below room temperature.

2. In a process for producing an antioxidant concentrate, the steps comprising contacting an oil-bearing vegetable material with ammonia, contacting the treated material with a solvent substantially miscible with fatty materials at room temperature and only partially miscible therewith at temperatures somewhat below room temperature, and separating a solvent solution containing a highly active antioxidant extract from the treated material and the fatty material therein immiscible with the solvent at the temperature somewhat below room temperature.

3. In a process for producing an antioxidant concentrate, the steps comprising contacting an oil-bearing vegetable material with ammonia, removing fatty material from the oil-bearing vegetable material, contacting the fatty material with a solvent substantially miscible with fatty ma-

terials at room temperature and only partially miscible therewith at temperatures somewhat below room temperature, and separating a solvent solution containing a highly active antioxidant extract from the fatty material immiscible with the solvent at the temperature somewhat below room temperature.

4. In a process for producing an antioxidant concentrate, the steps comprising contacting a crude vegetable oil with ammonia in the presence of a solvent for fatty materials, contacting the ammonia-treated oil with a solvent substantially miscible with fatty materials at room temperature and only partially miscible therewith at temperatures somewhat below room temperature, and separating a solvent solution containing a highly active antioxidant extract from the oil immiscible with the solvent at the temperature somewhat below room temperature.

5. In a process for producing an antioxidant concentrate, the steps comprising contacting an oil-bearing vegetable material with ammonia in the presence of a solvent for fatty materials, removing fatty material from the oil-bearing vegetable material, contacting the fatty material with a solvent substantially miscible with fatty materials at room temperature and only partially

miscible therewith at temperatures somewhat below room temperature, and separating a solvent solution containing a highly active antioxidant extract from the fatty material immiscible with the solvent at the temperature somewhat below room temperature.

6. In a process for producing an antioxidant concentrate, the steps comprising contacting a crude vegetable oil with ammonia in the presence of a solvent for fatty materials, heating the mass for a short time at the reflux temperature of the solvent, contacting the ammonia-treated oil with a solvent substantially miscible with fatty materials at room temperature and only partially miscible therewith at a temperature somewhat below room temperature, and separating a solvent solution containing a highly active antioxidant extract from the oil immiscible with the solvent at the temperature somewhat below room temperature.

7. In a process for producing an antioxidant concentrate, the steps comprising contacting an oil-bearing vegetable material with ammonia in the presence of a solvent for fatty materials, heating the mass for a short time at the reflux temperature of the solvent, removing fatty materials from the oil-bearing vegetable material, contacting the fatty material with a solvent substantially miscible with fatty materials at room temperature and only partially miscible therewith at a temperature somewhat below room temperature, and separating a solvent solution

containing a highly active antioxidant extract from the fatty material immiscible with the solvent at the temperature somewhat below room temperature.

8. In a process for producing an antioxidant concentrate, the steps comprising contacting a crude vegetable oil with ammonia in the presence of a solvent for fatty materials, heating the mass for a short time at the reflux temperature of the solvent, contacting the ammonia-treated oil with a solvent substantially immiscible with fatty materials at room temperature and only partially miscible therewith at a temperature somewhat below room temperature, cooling the solution of solvent and oil to a temperature somewhat below room temperature thus causing the solution to separate into a solvent solution layer and a layer of oil immiscible with the solvent, and separating the solvent solution containing a highly active antioxidant extract from the oil immiscible therewith at the low temperature.

9. In a process for producing an antioxidant concentrate, the steps comprising contacting an oil-bearing vegetable material with ammonia in the presence of a solvent for fatty materials, heating the mass for a short time at the reflux temperature of the solvent, removing fatty materials from the oil-bearing vegetable material, contacting the fatty material with a solvent substantially miscible with fatty materials at room temperature and only partially miscible therewith at a temperature somewhat below room temperature, cooling the solution of solvent and fatty material to a temperature somewhat below room temperature thus causing the solution to separate into a solvent solution layer and a layer of fatty material immiscible with the solvent, and separating the solvent solution containing a highly active antioxidant extract from the fatty material immiscible therewith at the low temperature.

10. In a process for producing an antioxidant concentrate, the steps comprising contacting a crude vegetable oil with ammonia in the presence of a solvent for fatty materials, heating the mass for a short time at the reflux temperature of the solvent, contacting the ammonia-treated oil at a temperature above room temperature with a liquid aliphatic, polar organic compound containing at least three carbon atoms and which is substantially miscible with fatty material at room temperature and only partially miscible therewith at a temperature somewhat below room temperature, the ratio of solvent to oil being greater than one, cooling the mass to a temperature somewhat below room temperature whereby layers are formed, and separating the solvent layer containing a highly active antioxidant extract from the oil layer.

11. In a process for producing an antioxidant concentrate, the steps comprising contacting an oil-bearing vegetable material with ammonia in the presence of a solvent for fatty materials, heating the mass for a short time at the reflux temperature of the solvent, removing fatty material from the oil-bearing vegetable material by extraction with a solvent for fatty materials, contacting the fatty material at a temperature above room temperature with a liquid aliphatic, polar organic compound containing at least three carbon atoms and which is substantially miscible with the fatty material at room temperature and only partially miscible therewith at a temperature somewhat below room temperature, the ratio of solvent to fatty material being greater

than one, cooling the mass to a temperature somewhat below room temperature whereby layers are formed, and separating the solvent layer containing a highly active antioxidant extract from the remainder of the fatty material.

12. In a process for producing an antioxidant concentrate, the steps comprising contacting a crude vegetable oil with concentrated ammonium hydroxide in the presence of a solvent for fatty materials, heating the mass for a short time at the reflux temperature of the solvent, contacting the ammonia-treated oil at a temperature above room temperature with an aliphatic monohydroxy alcohol containing from 3 to 6 carbon atoms, the ratio of solvent to oil being greater than 1, cooling the mass to a temperature somewhat below room temperature whereby layers are formed, and separating the solvent layer containing a highly active antioxidant extract from the oil layer.

13. In a process for producing an antioxidant concentrate, the steps comprising contacting an oil-bearing vegetable material with concentrated ammonium hydroxide in the presence of a solvent for fatty materials, heating the mass for a short time at the reflux temperature of the solvent, removing fatty materials from the oil-bearing vegetable material by extraction with a solvent for fatty materials, contacting the fatty material at a temperature above room temperature with an aliphatic monohydroxy alcohol containing from 3 to 6 carbon atoms, the ratio of solvent to fatty material being greater than 1, cooling the mass to a temperature somewhat below room temperature whereby layers are formed, and separating the solvent layer containing a highly active antioxidant extract from the remainder of the fatty material.

14. In a process for producing an antioxidant concentrate, the steps comprising contacting a crude vegetable oil with concentrated ammonium hydroxide in the presence of a solvent for fatty materials, heating the mass for a short time at the reflux temperature of the solvent, contacting the ammonia-treated oil at a temperature above room temperature with isopropanol, the ratio of solvent to oil being greater than 1, cooling the mass to a temperature somewhat below room temperature whereby layers are formed, and separating the solvent layer containing a highly active antioxidant extract from the oil layer.

15. In a process for producing an antioxidant concentrate, the steps comprising contacting an oil-bearing vegetable material with concentrated ammonium hydroxide in the presence of a solvent for fatty materials, heating the mass for a short time at the reflux temperature of the solvent, removing fatty materials from the oil-bearing vegetable material by extraction with a solvent for fatty materials, contacting the fatty material at a temperature above room temperature with isopropanol, the ratio of solvent to fatty material being greater than 1, cooling the mass to a temperature somewhat below room temperature whereby layers are formed, and separating the solvent layer containing the highly active antioxidant extract from the remainder of the fatty material.

16. In a process for producing an antioxidant concentrate, the steps comprising contacting a crude vegetable oil with concentrated ammonium hydroxide in the presence of acetone, heating the mass for a short time at the reflux temperature of the acetone, removing the acetone from the oil by distillation, contacting the oil at a tempera-

ture above room temperature with isopropanol, the ratio of solvent to oil being greater than 1, cooling the mass to a temperature somewhat below room temperature whereby layers are formed, and separating the solvent layer containing a 5 highly active antioxidant extract from the oil layer.

17. In a process for producing an antioxidant concentrate, the steps comprising contacting an oil-bearing vegetable material with concentrated 10 ammonium hydroxide in the presence of acetone, heating the mass for a short time at the reflux temperature of the acetone, removing fatty materials from the oil-bearing vegetable material by extraction with ethylene dichloride, contacting 15 the fatty material at a temperature above room temperature with isopropanol, the ratio of solvent to fatty material being greater than 1, cooling the mass to a temperature somewhat below room temperature whereby layers are formed, 20

and separating the solvent layer containing the highly active antioxidant extract from the remainder of the fatty material.

LORAN OID BUXTON.
